UNITED STATES PATENT OFFICE.

NICHOLAS LEWIS GULLIFORD, OF PEABODY, MASSACHUSETTS, ASSIGNOR TO GREGORY & READ COMPANY, OF BOSTON, MASSACHUSETTS, A CORPORATION OF MASSACHUSETTS.

HEEL-DROPPING MACHINE.

Application filed October 17, 1924. Serial No. 744,282.

My invention relates to heel trimming mechanisms and particularly to a heel "dropping" mechanism for operating upon the top or heel seat portion of a wood heel to give the breast end thereof a curvature or shape that is counterpart of the shape of that portion of the sole of the boot or shoe against which it fits.

To these ends I have provided a mechanism comprising a cutter adjacent which is arranged a work rest and heel engaged means, the latter serving, when engaged by the heel, to cause the cutter to operate upon the breast end portion of the heel seat of a heel and bevel or "drop" the same when the heel is slid on said work rest toward said means. In the preferred form of my invention said means comprises a cam so disposed that when a heel, occupying a position upon the work rest, is slid on the latter toward the cam the latter causes the cutter to engage the corner portions at the opposite sides of the breast of the heel seat and bevel the same, preferably upon a curve corresponding, approximately, with the curvature of the shank portion of the sole against which it is to fit. In the best form of my invention the engagement of the cutter with the heel is brought about through a tilting movement imparted to the heel by the cam. Also, a gauge is preferably provided adjacent the cutter, at the side thereof opposite the work rest, to engage the breast end of the heel to position the latter when first placed against the work rest.

Other features of my invention are hereinafter pointed out.

In the accompanying drawings:

Figure 1 is a plan view of a wood heel dropping machine constructed in accordance with my invention.

Figure 2 is a section on line 2-2 of Fig. 1.

Figure 3 is a perspective view of a wood heel before it is operated upon by the machine shown in Figs. 1 and 2.

Figure 4 is a perspective view of the same heel after being operated upon.

Figure 5 is a side elevation of the heel shown in Fig. 4.

Herein I have shown my invention embodied in a wood heel dropping machine comprising a frame 1 provided with legs to rest upon a bench or other support to which

the frame may be secured. Frame 1 is more or less rectangular in form and is made at opposite sides thereof with bearings 2, 2 which may, if desired, be ball bearings, said bearings receiving the shaft 3 of cutter 4. On the shaft 3 is fastened a pulley 5 through which the cutter is driven rapidly in the direction of the arrow, Fig. 2 by means of a belt (not shown).

Alongside of the cutter 4 the frame 1 is made with a cross-bar 6 to which a work rest plate or bar 7 is fastened by screws 8, the top side of this work rest being flat and substantially tangent to the path of the cutting edges of cutter 4. At the opposite side of cutter 4 is arranged a carriage 9 slidably mounted at each side in ways 10 on frame 1, said carriage being made upon its under side with a depending lug having a threaded aperture receiving a screw 11 by means of which the carriage may be adjusted toward and from the cutter 4 and work rest 7, and by which said carriage is held rigidly in adjusted position. At its outer end screw 11 is provided with a hand wheel 12.

To the top side of carriage 9 a gauge bar 13 is fastened by means of screws 14, said bar serving as an abutment against which the breast of the heel is placed as indicated by dotted lines in Fig. 1.

Adjacent work rest 7 is provided a second carriage 14' slidably mounted at each side thereof in ways 15 provided within frame 1, and this carriage is also made upon its under side with a depending lug formed with a threaded aperture receiving a screw 16 by means of which the carriage may be adjusted toward and from the cutter and work rest, and by which said carriage is held rigidly in adjusted position. At its outer end screw 16 is provided with a hand wheel 17.

Pivotedly connected at 18 to the end of carriage 14' adjacent work rest 7 is a cam plate 19 that is supported in an inclined or oblique position relatively to the plane of the top of the work rest by the upper end of a vertical screw 20, said screw being mounted in a threaded aperture provided through the carriage 14' and equipped at its lower end with a hand wheel 21.

Wood heels such as are commonly used upon women's shoes are made, as shown in Fig. 3, with a concaved top or heel seat 22

and with a breast having a thin forwardly extending shank lip 23 whose top side edges, one of which is indicated by dotted lines at 24 in Fig. 5, are originally formed in the same place with the outer edge of the rear portion of the heel seat. Owing to the distance to which the shank lip extends forwardly along the shank portion of the sole into the curve of the arch of the shank, it is 10 customary to bevel or "drop" the side edge portions 24 of the shank lip as shown in Fig. 5 so that they will conform to the downward curve of the shank portion of the sole. My machine performs this beveling operation which is carried out as follows: The wood heel H, Fig. 3, is placed upon the work rest 7, bottom side up, with its breast end resting against gauge 13 and its back end at or near the foot of the cam 19 after which the heel 15 is slid on the work rest toward cam 19. As the back end of the heel moves up the incline or cam 19 the heel pivots on the transverse corner 25 of the work rest and the sides of the shank lip 23 are thereby swung down 20 into the path of the cutting blades of cutter 4 so that said sides are beveled off by the cutter upon a curve as shown in Fig. 5.

What I claim is:

1. A heel dropping mechanism comprising 30 a cutter; a work rest adjacent said cutter occupying a fixed and immovable position with relation to the latter, and heel engaging means adjacent said work rest for tilting the heel to cause the cutter to engage the breast end portion of the heel seat of a heel and bevel the same when the heel is slid on said work rest toward the said means.

2. A heel dropping mechanism comprising 40 a cutter; a work rest adjacent said cutter occupying a fixed and immovable position with relation to the latter, and means adjacent said work rest for tilting the heel to cause the cutter to engage the breast end portion of the heel seat thereof when the heel is slid on said work rest toward said means.

3. A heel dropping mechanism comprising 50 a cutter; a work rest adjacent said cutter occupying a fixed and immovable position with relation to the latter, and a cam adjacent said work rest to cause the cutter to engage the breast end portion of the heel seat of a heel when the latter is slid on said work rest toward said cam.

4. A heel dropping mechanism comprising 60 a cutter; a work rest adjacent said cutter occupying a fixed and immovable position with relation to the latter, and a heel engaging cam adjacent said work rest to tilt the heel on said work rest to cause the cutter to engage the breast end portion of the heel seat thereof when the heel is slid on said work rest toward said cam.

5. A heel dropping mechanism comprising 70 a cutter; a work rest adjacent said cutter

occupying a fixed and immovable position with relation to the latter; heel engaging means adjacent said work rest to tilt the heel on said work rest to cause the cutter to engage the breast end portion of the heel seat thereof when the heel is slid on said work rest toward said means, and a heel engaging and positioning gauge adjacent said cutter.

6. A heel dropping mechanism comprising 75 a cutter; a work rest adjacent said cutter occupying a fixed and immovable position with relation to the latter; a heel engaging cam adjacent said work rest to tilt the heel on said work rest to cause the cutter to engage the breast end portion of the heel seat thereof when the heel is slid on said work rest toward the cam, and means to provide for adjusting the throw of said cam.

7. A heel dropping mechanism comprising 80 a cutter; a work rest adjacent said cutter occupying a fixed and immovable position with relation to the latter; heel-engaging means adjacent said work rest to tilt the heel on said work rest to cause the cutter to engage the breast end portion of the heel seat thereof when the heel is slid on said work rest toward 85 said means, and means to provide for adjustment of said means toward and from said cutter.

8. A heel dropping mechanism comprising 90 a cutter; a work rest adjacent said cutter and occupying a fixed position with relation thereto; a cam adjacent said work rest serving to tilt the heel on said work rest to cause 95 the cutter to engage the breast end portion of the heel seat thereof when the heel is slid on said work rest toward the cam; a heel engaging and positioning gauge adjacent 100 said cutter, and means to provide for adjustment of said gauge toward and from 105 said cutter.

9. A heel dropping mechanism comprising 110 a frame; a cutter rotatably mounted on said frame; a heel tilting cam on said frame, and 115 a fixed and immovable heel support between said cam and said cutter and immediately adjacent the latter to engage and support the heel seat end of a heel in position immediately alongside of said cutter with provision 120 for sliding movement of the heel thereon and on said cam to cause the latter by engagement with the heel to tilt the latter thereby to cause the cutter to engage and bevel only the rear portion of the seat of the heel adjacent the breast thereof.

10. A heel dropping mechanism comprising 125 a frame; a cutter rotatably mounted on said frame to which heels are manually presented to be operated upon, and fixed and immovable heel guiding and supporting means against which the heel is manually held and on which the heel is manually slid and by which the heel is automatically tilted as it is slid thereon to cause the cutter 130

to bevel only a portion of the heel seat end of the heel adjacent the breast of the latter and at each side thereof.

11. A heel dropping mechanism comprising a cutter; a work-rest adjacent said cutter, and fixed and immovable means adjacent said work-rest adapted for engagement with the heel constructed and arranged so that when

the heel is positioned on said work-rest and slid on the work-rest and said means away ¹⁰ from the cutter the breast end portion of the heel will be swung into the path of the cutter and the latter will bevel the rear end thereof.

NICHOLAS LEWIS GULLIFORD.
